CLAIM

The ornamental design for a breast pump accessory as shown and described.

DESCRIPTION

FIG. 1 is a front view of a breast pump accessory according to the claimed design;

FIG. 2 is a rear view thereof;

FIG. 3 is a right side view thereof;

FIG. 4 is a left side view thereof;

FIG. 5 is a top elevation view thereof;

FIG. 6 is a bottom elevation view thereof;

FIG. 7 is a front right perspective view thereof; and,

FIG. 8 is a rear left perspective view thereof.

The broken lines in the figures show portions of the breast pump accessory that form no part of the claimed design.

1 Claim, 8 Drawing Sheets(56)
